UNITED STATES PATENT OFFICE.

MEYER HERMAN, OF CHICAGO, ILLINOIS.

SCAFFOLD.

1,404,394.

Specification of Letters Patent. Patented Jan. 24, 1922.

Application filed February 28, 1921. Serial No. 448,430.

To all whom it may concern:

Be it known that I, MEYER HERMAN, a citizen of the United States, residing at Chicago, in the county of Cook and State of Illinois, have invented certain new and useful Improvements in Scaffolds, of which the following is a specification:

The invention relates to improvements in scaffolds.

10 One of the objects of the invention is to provide an improved, foldable and extensible scaffold, that may be made to occupy a minimum space when folded and which may be extended in length and height to accommodate any conditions of work.

The scaffold is intended for use by decorators, paper hangers, painters, and the like, and is especially adaptable for such use because of its capability of being compacted 20 into small dimensions convenient for transportation.

One of the particular objects of the invention is to provide end supports that are rigidly stable when laterally extended for use so that the suspended platform will not materially sway or totter under the superimposed weight of the workman supported thereon.

Another object is to provide at each end 30 of the structure folding steps by means of which the workman may conveniently ascend or climb up to the platform with very little effort or loss of time.

Another object is to provide a scaffold in 35 which all of the parts are joined together so that liability of leaving any of the parts at the place where the structure is used is eliminated.

Other, further and more specific objects 40 of the invention will become readily apparent, to persons skilled in the art, from a consideration of the following description, when taken in conjunction with the accompanying drawings, wherein:

Fig. 1 is a side elevation of the scaffold extended for use, showing in dotted lines one of the end supports or trestles folded.

Fig. 2 is an end elevation of Fig. 1.

Fig. 3 is an enlarged section taken on line 50 3-3 of Figs. 1 and 2.

Fig. 4 is a sectional plan view of one end on an enlarged scale, this section being taken on line 4-4 of Fig. 5.

Fig. 5 is a section taken on line 5-5 of 55 Fig. 4.

Fig. 6 is a plan view of the scaffold when folded.

Fig. 7 is a section taken on line 7-7 of Fig. 3.

Fig. 8 is a section through the pivoted ends 60 of a pair of legs.

In all the views the same reference characters are employed to indicate similar parts.

The device consists of two folding trestles, 10 and 11, and an extensible platform pivotally connected at each end to the respective trestles through a vertically slidable support to form a scaffold. As both of the trestles are substantially alike I will describe only one, with the understanding that all that is 70 to be said about the one will apply with equal force and effect to the other.

Each trestle is provided with four diverging legs, two inner legs 13-13' and two outer legs 14-14'. The legs 13 and 14 are 75 arranged with respect to each other so that their widest sides are at right angles. The legs 14 bear upon the upper end a metal cap 15. The part or cap 15 extends around the upper ends of each of the legs 14, and over 80 the top, as clearly shown in Fig. 8, and within which the legs 13 are pivoted, as at 16. A metal strip 17 is also passed around the upper ends of the legs 13, through which the rivet 16 passes in order to strengthen and 85 protect the upper ends of these legs.

An angle iron 18 is bent around the upper end of the legs 14 and is held in place by the bolts 19 which pass through it and through the side walls of the cap 15. A bolt 20 90 passes through the upper end of the legs 14 and is pivotally connected to a suspended frame 21 and is the means by which the leg structure, at the respective sides of the scaffold, may swivel.

The frame comprises two vertically depending, parallel members 22, which suspend from the bolt 20 and which have, at intervals, notches 23. The lower end of the members 22 are connected to the respective ends 100 of a cross member 24, as at 25. The platform supporting frame 26 consists of the side plates 27 and 28, made in a box-like form by the horizontal walls 29-30, the parts being secured together by any proper means.

End plates 31 and 32 provide guides for movement on the vertical, parallel members 22 and 22'. The platform 12 is supported on the frame member 26 by the hinge members 34 and 35. The platform consists of two 110

relatively sliding members made of alternating bars 36 and 37, that are capable of being longitudinally extended and which are connected together by cleats 38 and 38', respectively.

Inside of the structure 26 are pivoted latch members or spring-pressed dogs 40 and 41, pivoted to the side plates 27 and 28. The latch dogs 40 and 41 are held yieldingly outwardly extended by a doubled ended spring 43, to yieldingly engage the notches 23-23', respectively, in the frame 21.

Near the center of the structure 26 and on the inside thereof is a plate 44 secured to a 15 rotatable latch member 45 which extends outside of the casing in the handle 45'. Links 46 are pivoted to the plate 44 and to the respective dogs 40 and 41, so that when the handle 45' is rotated, the dogs will be there- 20 by removed from the notches with which they engage.

Now, it will be apparent that, when the dogs are removed in this manner from the notches that the end of the platform 12, 25 which is supported upon the vertically slid- able frame structure 26, may be adjusted in vertical position to change the height of the platform by causing the dogs to engage any pair of the vertical series of the notches 23 30 in the frame members 21. By this means the platform may conveniently be raised or lowered to suit the workman and to conform to the height of the ceiling or the wall upon which he may be working.

Pivoted to each of the legs 14 and 14' is a 35 link 49-49'. They diverge inwardly and are connected to the two cross bars 50 and 51. Similarly, 52 and 52' are connected to the legs 13-13', respectively, and they are 40 pivoted to the links 49-49', as at 53-53'. The bar 51 is outwardly deflected, as at 54, and the outwardly deflected part contains a notch to overlie the bar 24 to hold the latter in vertical position and prevent the frame 45 and platform from swinging.

Each pair of legs, 13 and 14, is pivoted by the bolt 20-20', so as to move outwardly with respect to the members 22 and 22', and the legs 13 and 14 move outwardly and di- 50 verge from each other, as shown in Fig. 1, being held in this position by means of the links 49 and 52.

Two part cross braces 55 and 56 are pivoted, as at 57 and 58, to the respective pair 55 of legs 14. Each of these braces are pivoted together, as at 59, and are held in aligning position by a part of one brace engaging in a notch of the other, as at 60, so that the legs 14 may be brought into parallel relation 60 when the device is to be folded, as clearly shown in Fig. 6.

A cross link consisting of two parts, 62 and 63, hinged at the points 58 to the legs 14 and 14', respectively, are also hinged together, as at 64. The part 65 holds them in

aligning position. This composite brace holds the legs extended, as clearly shown in Fig. 2.

A step or arm 66 is pivoted, as at 67, to the leg 13 and extends outwardly where it is pivoted, as at 68, to a vertical link 69, the latter being pivoted to the cross brace 52, as at 70. The arm 66 and the brace 52 serve as steps to assist the operator in mounting to the platform 12. 75

Hinged straps 71 and 72 are pivotally connected to the legs 13 and 14 to extend across on either side of the structure when folded together, as more clearly shown in Fig. 6, for the purpose of holding the parts in col- 80 lapsed positions.

While I have herein shown a single embodiment of my invention for the purpose of clear disclosure, it will be manifest to persons skilled in the art that many changes 85 may be made in the general form and arrangement of the parts, within the scope of the appended claims.

Having described my invention, what I claim as new and desire to secure by Letters 90 Patents, is:—

1. A device of the character described having two like trestles, each trestle comprising four diverging legs, a pair on each side; a platform supporting frame, sus- 95 pended from and hinged to each pair of legs and extending downwardly to a point near the vertical mid-portion of the trestles; holding means connecting the lower end of the frame to each of the legs; a two part 100 platform having two axially slid- able members; a vertically movable latch structure on each of said frames pivotally connected to the respective members of the platform to vertically adjust the latter and to hold it in 105 adjusted position, and holding means to hold the legs distended.

2. A device of the character described having two like trestles, each trestle comprising four diverging legs, a pair on each 110 side; a platform-supporting frame sus- pended from and hinged to the top of each pair of legs and extending downwardly to a point near the vertical mid-portion of the trestle, each vertical frame member having 115 spaced apart notches for a latch; holding means for connecting the lower end of the frame to the legs; a two-part platform hav- ing two axially slid- able members; a ver- 120 tically movable latch structure on said frame pivotally connected to the respective mem- bers of the platform having a pair of spring-pressed dogs to engage the notches in the respective vertical members, to vertically adjust the platform and to hold it in ad- 125 justed position, and holding means to hold the legs distended.

3. A device of the character described comprising a two part slid- able platform, a trestle connected to the respective ends of 130

the platform, each trestle having four diverging legs divided into two pairs, the wide portion of a leg of each pair being in a plane at right angles to a similar leg to which it is hinged; a frame comprising two vertically disposed side members, notched at intervals and hinged to the top ends of the adjacent pairs of legs; a vertically movable support hinged to the adjacent end 10 of the platform and slidable on the respective member of the frame and a latch carried by the support to engage the notches in the side members in the frame to adjust the height of the platform.

15 4. A device of the character described comprising a platform; a trestle for sup-

porting the platform having four diverging legs hinged together at their top ends in pairs; a downwardly extending frame comprising two parallel vertical members having spaced apart notches and hinged at the upper ends to the respective pair of legs; a structure slideable vertically on said vertical members and hinged to the respective ends of the platform; a pair of spring-pressed 20 latch members in said structure for engaging the aforesaid notches and a lever for moving both members out of said notches.

In testimony whereof I hereunto subscribed my name.

MEYER HERMAN.
